UNITED STATES PATENT OFFICE

155,642

DESIGN FOR A BIB OR SIMILAR ARTICLE

Harry I. Strandhagen, Fort Lauderdale, Fla.

Application July 28, 1947, Serial No. 140,569

Term of patent 14 years

(Cl. D3—26)

To all whom it may concern:

Be it known that I, Harry I. Strandhagen, a citizen of the United States, residing in Fort Lauderdale, in the county of Broward and State of Florida, have invented a new, original, and ornamental Design for a Bib or Similar Article, of which the following is a specification, reference being had to the accompanying drawing, forming part thereof, in which:

Fig. 1 is a front elevational view of a bib embodying my new design;

Fig. 2 is a side elevational view thereof; and

Fig. 3 is a top plan view.

I claim:

The ornamental design for a bib or similar article, substantially as shown.

HARRY I. STRANDHAGEN.
